Primary Examiner — Ania Aman(74) *Attorney, Agent, or Firm* — Cheng-Ju Chiang(57) **CLAIM**

The ornamental design for a snow sled, as shown and described.

DESCRIPTION

FIG. 1 is a perspective view showing my design;
 FIG. 2 is a front view thereof;
 FIG. 3 is a back view thereof;
 FIG. 4 is a left side view thereof;
 FIG. 5 is a right side view thereof;
 FIG. 6 is a top view thereof;
 FIG. 7 is a bottom view thereof; and
 FIG. 8 is a cross-sectional view taken along line 8-8 in FIG. 6.
 FIG. 9 is a cross-sectional view taken along line 9-9 in FIG. 6.
 FIG. 10 is an enlarged cross-sectional view in a portion in FIG. 9; and,
 FIG. 11 is another perspective view thereof.
 The broken lines shown in the views depict environmental subject matter only and form no part of the claimed design.

1 Claim, 8 Drawing Sheets(56)
